UNITED STATES PATENT OFFICE.

ELIJAH NEFF, OF MILFORD, ASSIGNOR OF ONE-HALF TO J. C. WILLIARD,
OF FORT WAYNE, INDIANA.

PUMP.

SPECIFICATION forming part of Letters Patent No. 451,835, dated May 5, 1891.

Application filed January 29, 1891. Serial No. 379,570. (No model.)

To all whom it may concern:

Be it known that I, ELIJAH NEFF, a citizen of the United States, residing at Milford, in the county of Kosciusko and State of Indiana, 5 have invented a new and useful Pump, of which the following is a specification.

This invention relates to pumps for domestic purposes and to be used in cisterns, lakes, &c.; and the objects in view are to provide a 10 pump from which water may at all times be readily forced in a continuous and unbroken stream, either for garden or household purposes, and, furthermore, which may be connected and operated by a windmill, the latter 15 being thrown into and out of the wind by the pump.

With the above objects in view the invention consists in certain features of construction hereinafter specified, and particularly 20 pointed out in the claims.

Referring to the drawings, Figure 1 is a general view illustrating the applicability of my invention. Fig. 2 is a detail of the pump in vertical longitudinal section.

Like numerals of reference indicate like 25 parts in all the figures of the drawings.

1 designates the metal cap or base of the pump, the same being mounted over a cistern or supported over a lake or other source of 30 supply, and said base has depending from an opening in its center a collar or flange 2. At one side of the base is located a pump-casing 3, terminating in a discharge-spout 4, and diametrically opposite the same a bearing-lug 35 5 is provided, in which is pivoted a standard 6, having pivoted at its upper end, as at 7, a lever 8. The lever 8 at its outer end is provided with a socket 9, and in the same is removably fitted a pump-handle 10. At its opposite end the lever 8 is pivoted, as at 11, to the upper end of a cross head or yoke 12.

Depending from the collar or flange 2 of the base is the delivery-cylinder 13, provided at its center with a combined coupling and union 45 14, having diverging branches 15 and 16, communicating with the interior of the cylinder. To the lower end of the cylinder 13 there is coupled a cylinder 17, provided at diametrically-opposite sides with vertical slots 18, in 50 which is mounted for reciprocation a cross-head 19, the ends of which extend through

the slots and beyond the wall of the cylinder. The lower end of the cylinder 17 is by a coupling 20 connected to the pumping-cylinder 21, in the lower end of which is formed a valve-head 22, having an upwardly-opening valve 23, and to said head from the source of supply leads the pipe 24. The cylinder 13 is provided at its upper end with a head 25, and in the same is mounted a valve-chamber 26, 60 having a downwardly-opening valve 27.

28 designates a hollow piston or pump rod, which is mounted in a central opening formed in the cross-head 19, to the lower end of which is secured the piston-head 29, having a 65 valve-chamber 30 and an upwardly-opening valve 31, said piston being adapted for movement in the pump-cylinder 21. To the upper end of the hollow piston or pump rod is secured the piston-head 32, designed for movement in the delivery-cylinder 13 and to operate therein below the coupling 14, in which the delivery-port is formed. From a bridge 33 upon the upper side of the piston 32 there extends a hollow tubular piston 34, 70 75 which extends above the coupling 14, and is there secured to a valve-chamber 35, having a valve 36, and beyond the valve is a piston 37, mounted for movement in the upper portion of the discharge-cylinder. The opposite outer 80 ends of the cross-head are connected by means of connecting-rods 38 to the ends of the yoke 12, so that any movement upon the part of the yoke, as caused by the operation of the handle 10, causes a similar movement 85 upon the part of the internal system of hollow piston-rods, piston-heads, and valves. A pipe 39 connects the upper branch 15 of the delivery-cylinder with the discharge 4, said pipe being formed in sections and connected 90 by a cut-off 40.

41 designates a storage-tank, and the same comprises a cylindrical wall 42, the ends of which are inwardly turned and embrace and are riveted to, as at 43, opposite conical heads 95 44, the same being provided with upturned annular flanges 45, the edges of the wall and the heads being soldered to increase the tightness of the joint and rigidity of the parts. One head is provided with an inlet-opening 46 and the opposite head with an outlet-opening 47, in which latter is mounted a cut-off

or valve 48, the handle 49 extending up from the same to a point above the surface of the ground, whereby the water may be cut off at this point. This tank 41 is located either in 5 the lake or at such a depth in the ground as to prevent the contents thereof from freezing. A pipe 50 serves to connect the lower discharge branch 16 of the discharging-cylinder to a valve 51, and said valve is connected by 10 a pipe 52 to the inlet 46 of the tank 41. The service-pipe 53 is connected to the pipe 47 and leads to the house or other point of use, and in fact may be tapped at several points and connected with branch pipes 54, as shown 15 in Fig. 1.

55 designates a base or casting, and the same is provided with a central countersunk head 56, at each side of which are located guides 57, in which are mounted for reciprocation guide-rods 58, connected at their upper and lower ends by yokes 59 and 60, respectively, the latter being provided with a pair of perforated ears 61, between which is connected the lower end of a piston-rod 62, 25 that extends up through a central perforation 63 in the head 56 into a cylinder 64, mounted in the head and provided at its upper end with a head 65, having a central opening. Within the cylinder 64 there is mounted for 30 reciprocation a piston-head 66, which is connected to the upper end of the piston-rod 62, and coiled about the rod and interposed between the head 66 and the head 56 is a coiled spring 67, serving, when not otherwise influenced, to elevate the piston head and rod, 35 the guide-rods 58, and the yoke 59. A pipe 68 leads from the opening in the head 65, and by an elbow 69 is connected with the pipe 70, which latter is connected to a similar pipe 71 40 by a union 72, in which is mounted a valve 73 and an oil-cup 74. An elbow 75 serves to connect the end of the pipe 71 with a small pipe 76, to which latter is connected a cut-off 77, and the cut-off is connected with the tank 41 by means of a pipe 78, leading to the upper side of the tank.

This completes the construction of the pump, and the operation of the same is as follows: The downstroke of the connecting-rod 38, and consequently the cross-head 19, 50 lowers the hollow piston 28 and with it the piston-heads 37, 32, and 29, together with their valves. This causes the upper head 37 to draw air in the upper portion of the discharge-cylinder through the valve 27 and to force water contained in the pumping-cylinder 21 through the valve-chamber 30 up 55 through the hollow piston 28, through the openings in the bridge 33, into the discharge-cylinder 13. A reverse or upward movement 60 of the hollow piston-rod causes an inflow of water into the pumping-cylinder 21, through the valve-pipe 24, and forces water and air by the piston-head 32 out of the discharge 65 branches 15 and 16 in accordance with the branch that is open. The upward movement of the piston-head 37 causes air to be forced

through the valve-chamber 35 into the discharge-chamber 13. In this manner the tank 41 becomes filled with water and air, the air occupying the upper portion of the tank and the water the lower portion thereof. By opening the cut-off 40 of the hydrant or discharge 70 39, water will flow from the tank and be forced by the compressed air therein through the 75 pipes 52 50 39 to the hydrant, or, if the pump be in motion, water will be pumped direct from the source of supply. By opening the valve 48 through its rod 49 the service system to the house is thrown into communication 80 with the tank 41, all water passing therethrough and being governed by suitable faucets within the house being forced by the compressed air within the tank 41. 79 designates the pump-rod of a windmill, which is 85 connected to the cross-head 12 at the point 11, so that the pump may be operated thereby. A wire 80 leads from the governor of the mill to the yoke 59 of the reciprocating rods 58, so that any movement upon the part of said rods 90 or of the frame which they constitute is transmitted to the governor and the mill either thrown into or out of the wind. The compressed air in the tank 41 passes up through the pipe 78, the cut-off 77, when the latter is 95 open, and through the pipes 75, 71, 70, 69, and 68 into the cylinder 64, where it acts upon and, when sufficient, depresses the piston-head 66 against the tension of its spring 67. As the head lowers, so also does the rod 62, 100 and, by reason of its connection with the yoke 60, the yoke and sliding frame, of which it is a part, also lowers. This lowering of the yoke and its frame serves to indicate that the water in the tank is under compression by the 105 air, and hence the operation of the mill is not required, and through the medium of the wire 80 the wheel of the mill is thrown out of the wind. When, however, the air and water fall within the tank and the air is insufficient to compress the piston-head 66, the 110 spring 67 serves to raise the head and with it the sliding frame, and thus release the windmill, so that the wheel of the same is thrown into and adapted to be operated by 115 the wind, and thus through the medium of its rod operate the pump.

Having described my invention, what I claim is—

1. The combination, with the discharge-cylinder provided at its upper end with an inlet air-valve and a pumping-cylinder, of a hollow piston terminating in the pumping-cylinder in a piston-head and at its upper end in the lower portion of the discharge-cylinder in 125 a head, the piston-head being provided with a valve, a piston-rod connected with the upper head and terminating at its upper end in the upper end of the discharge-cylinder, a head having an inlet-valve secured thereto, a 130 storage-tank having a discharge, a pipe connecting the storage-tank to the discharge-cylinder, and means for operating the hollow piston, substantially as specified.

2. The combination, with the delivery-cylinder, of the pump-cylinder located below the same, the open piston-head mounted in the lower portion of the delivery-cylinder, the valve piston-head mounted in the pump-cylinder and the valve piston-head mounted in the upper portion of the delivery-cylinder, the upper end of which is valved, the hollow piston connecting the open piston-head of the delivery-cylinder with the valved head of the pump-cylinder, the secondary piston-rod connecting the open piston-head with the upper piston-head, the cross-head 19, connected to the hollow piston, the connecting-rods connected to the cross-head, the upper cross-head 12, connected to the rods, the lever 8, its support 6, the storage-tank 41, the pipe connecting the same with the delivery-cylinder, and the discharge connected with the tank, substantially as specified.
3. The combination, with the delivery-cylinder formed in sections, of the coupling 14, connecting the same and having the discharge branches 15 and 16, an air-induction pipe and pump leading to the cylinder, a water-induction pipe and pump leading to the same, the opposite piston-heads mounted at each side of the coupling 14, means for operating the same, the hydrant having the cutting off, the pipe connecting the same with the branch 15, the storage-tank, the discharge thereof, and the pipe connecting the branch 16 with the storage-tank, substantially as specified.
4. The combination, with the base 1, the fulcrum 6, the lever 8, the cross-head 12, the depending flange 2, the hydrant-case 3, and the discharge-pipe 39, having the cut-off 40, of the cylinder 13, having the head 25 at its upper end, the valve 26, mounted on the head, the cylinder 17, coupled to the lower end of the cylinder 13 and having the opposite slots 18, the cylinder 21, coupled to the lower end of the cylinder 17 and having the valve 22, the pipe 24, leading to said valve, the piston 29, having the valve 30 mounted in the cylinder 21, the hollow piston 28, connected to the valve 30, the cross-head 19, mounted in the slots 18 and secured in the center to the hol-
- low piston, the piston-head 32, mounted in 50 the lower end of the cylinder 13 and having a central opening, the bridge 33, the head 37, mounted in the upper end of the cylinder 13 and having the inlet-valve 36, the hollow piston 34, connecting the valve with the 55 bridge, the coupling 14, connecting the sections of the cylinder 13 and having the branches 15 and 16, the former connected with the pipe 39, the tank 41, having the discharge 47 and inlet 46, the valve 50, the pipe 60 51, connecting the valve with the branch 16, and the pipe 52, connecting the inlet with the valve, substantially as specified.
5. The combination, with the water and air pumps and the storage-tank connected therewith and provided with a discharge, of an air-cylinder, a pipe leading from the cylinder to the tank, a piston-head seated upon a spring within the cylinder, and a windmill-regulating wire connected with and actuated 70 by the head, substantially as specified.
6. The combination, with water and air pumps, means for operating the same, and a storage-tank communicating therewith and provided with a discharge, of a base, a sliding 75 frame mounted in the base, a piston-rod secured to the frame, a cylinder the head of which receives the rod, a piston-head mounted on the rod within the cylinder, a spring for elevating the piston-head, an air-pipe leading to the cylinder, and a windmill-regulating wire connected to the frame, substantially as specified.
7. In a water system, the storage-tank consisting of a cylindrical wall having its ends 85 inwardly turned, opposite conical heads having upturned peripheral flanges mounted in the ends of the cylinder and riveted thereto, a bar passing through the head, and nuts mounted on the end of the bar and clamping 90 the heads, substantially as specified.
- In testimony that I claim the foregoing as my own I have hereto affixed my signature in presence of two witnesses.

ELIJAH NEFF.
